UNITED STATES PATENT OFFICE.

ALBERT OLESON, OF TOLEDO, OHIO.

DESIGN FOR A POMMEL-SPRING FOR BICYCLE-SADDLES.

SPECIFICATION forming part of Design No. 33,549, dated November 13, 1900.

Application filed October 8, 1900. Serial No. 32,453. Term of patent 7 years.

To all whom it may concern:

Be it known that I, ALBERT OLESON, of Toledo, county of Lucas, and State of Ohio, have invented and produced a new and original 5 Design for a Pommel-Spring for Bicycle-Saddles; and I do hereby declare that the following is a full, clear, and exact description thereof, which will enable others skilled in the art to which it appertains to make and use 10 the same, reference being had to the accompanying drawings, and to the figures of reference marked thereon, which form part of this specification.

My invention has reference to a new and 15 original design for a pommel-spring for bicycle-saddles.

In the drawings, Figure 1 is a side elevation of my spring to disclose the design thereof. Fig. 2 is a front elevation to more fully 20 disclose the design. Fig. 3 is a plan view of the same.

The essential feature of my new design is a spring comprising a plurality of approximately-ellipsoidal convolutions terminating in an eye at each end of the spring. As shown ²⁵ in the drawings, 1 is the spring, having the ellipsoidal convolutions 2. These, as shown, are gradually reduced in size as they approach the ends of the spring, as at 3, and terminate in eyes 4.

Having described my new design, what I claim, and desire to secure by Letters Patent, is—

The design for a pommel-spring for bicycle-saddles, substantially as shown and described. ³⁵

In testimony that I claim the foregoing as my own I affix my signature in presence of two witnesses.

ALBERT OLESON.
